UNITED STATES PATENT OFFICE.

ANDREW D. WYCKOFF, OF MAYWOOD, AND HOWARD P. DE CORREVONT, OF CHICAGO, ILLINOIS, ASSIGNORS TO OIL PRODUCTS APPLIANCE CO., OF MAYWOOD, ILLINOIS, A CORPORATION OF ILLINOIS.

DRIP-PAN ASSEMBLY.

Application filed January 8, 1921. Serial No. 435,840.

To all whom it may concern:

Be it known that we, ANDREW D. WYCKOFF, a citizen of the United States, and a resident of Maywood, Cook County, and State of Illinois, and HOWARD P. DE CORREVONT, a citizen of the United States, and a resident of Chicago, Cook County, and State of Illinois, have invented certain new and useful Improvements in Drip-Pan Assembly, of which the following is declared to be a full, clear, and exact description.

This invention relates to drip pan assembly for oil or other liquid dispensing apparatus, and among its principal objects are to simplify, cheapen and otherwise improve upon devices of this character.

In service stations, garages, and other establishments where oil or other valuable liquid is dispensed from a tank or receptacle, provision must be made against the unauthorized withdrawal or theft of the liquid. To guard against loss of oil, caused by its dripping from the discharge spout of the delivery arm, and to prevent malicious persons from introducing abrasive or other materials into the tank containing the oil, provision must be made for sealing up all openings to the tank when oil is not being dispensed therefrom, and many attempts have been made to accomplish such objects. One of the objects of this invention is to provide improved means for avoiding loss of the oil due to the dripping thereof from the discharge spout, and from unauthorized removal or theft. Other objects and advantages will appear in the course of the following specification and with all of said objects and advantages in view this invention consists in the novel features of construction, arrangement and combination of parts, hereinafter fully set forth and claimed.

The invention is clearly illustrated in the accompanying drawing, in which:

Fig. 1 is a view, partly in side elevation and partly in vertical section, of a tank, its discharge arm and a drip pan assembly, embodying a simple form of the present invention; Fig. 2 is a plan of the pan and its cover partly broken out; Fig. 3 is a side elevation of a fragment of the drip tube; Fig. 4 is a detail, horizontal section taken on the line 4-4 of Fig. 1; Fig. 5 is a side elevation of a measuring stick or gauge used in connection with the device; Fig. 6 is a plan

partly broken out of a slightly modified form of the drip pan and cover; Fig. 7 is a vertical cross section taken on line 7-7 of Fig. 6 and Fig. 8 is a detail, cross section taken on line 8-8 of Fig. 7.

Referring to said drawings, and first to Figs. 1 to 5, inclusive, which illustrate a simple embodiment of the present invention, the reference character 5 designates a fragment of a tank or receptacle for containing oil or other liquid to be dispensed. As is well understood, an oil or liquid pump or delivery apparatus (not shown) is mounted in the tank and serves to draw off the oil or liquid and discharge it into any suitable receptacle. The delivery or discharge pipe of such pump or dispensing apparatus is illustrated at 6 and has the usual goose neck nozzle 7 terminating in a downwardly projecting tubular spout 8. The parts described are old and common and require no detailed description, so far as this specification is concerned.

Directly below the spout 8, the tank 5 is formed with an opening 9 in which fits a flanged drip pan ring 10 which is fixedly secured to the top of the tank by bolts, rivets or like fastening devices 10a. The flange 11 of the ring extends down through the hole in the tank and has an annular inwardly projecting shoulder or ledge 12 formed thereon, on which is removably supported a grid or grate like drip pan structure 13, comprising a downwardly and centrally sloping bottom plate 14 formed at its marginal edge with an upwardly projecting annular flange 15. Said bottom part has a central opening 16 above which rises a hollow boss 17 and in said opening 16 is secured a fine mesh wire screen 18. Ribs 19 radiate from the hollow boss 17 to the flange 15 and the upper edges of said ribs 19, flange 15, and hollow boss 17 are flush with or approximately flush with the upper face of the ring 10. In the bottom plate 14 between two of the ribs 19 is a small hole 20, through which extends a measuring stick or gauge 21; said stick contains a scale whereby the quantity of liquid contained in the tank, can be readily determined. A handle 22 is secured to the top of the gauge and said handle is formed on a shouldered stopper like part 23 which projects through the hole 20 with its shoulder resting on the bottom

plate 14. The latter is preferably formed with a raised ridge around the hole 20, upon which the shoulder of the stopper rests.

To the ring 10 is rotatively and removably secured a cover plate 24, which rests on the ring 10 and is locked against movement by means which will be presently described. Conveniently, said pivotal connection between the cover plate and ring may comprise 10 a downwardly projecting hook like lug 25, secured in an ear 26 formed on the edge of the cover plate, said lug projecting down through a hole 27 in an ear 28 formed on the edge of the ring 10. Obviously, the cover 15 plate may be swung about on its pivotal connection with the ring 10 to uncover the drip pan 13, and may be detached from the ring by swinging the cover plate upward to disengage the hook 25 from hole 27.

20 The cover plate 24 is preferably made with a dome like part 29, at the center of which is an opening 30 surrounded by a threaded flange 31 and threadedly secured in said opening is a drip pipe 32 which projects up therefrom, to within a short distance 25 from the bottom of the discharge spout 8. Any drippings of oil from the spout fall through the pipe 32 and through the opening 16 and screen 18, and re-enter the tank 10.

30 To lock the cover plate 24 on the ring 10, and to prevent mischievous persons from introducing abrasive or other injurious material through the upper open end of the pipe 32 or from drawing off liquid from the tank, 35 even when the cover with its drip pipe is in place on the ring 10, I provide a short pipe 33 at the upper end of the drip pipe which may telescope into said drip pipe and which may be raised above the upper edge of said

40 drip pipe to thereby surround and enclose the discharge spout. As shown, the pipe 33 has an eye stud or apertured lug 34 secured to it, which projects out through a slot 35 in the drip pipe and rests on the lower edge of 45 said slot when the pipe is telescoped into the drip pipe. Said slot 35 is substantially L-shaped, comprising a vertical part 36 terminating at its upper end in a slightly upwardly inclined part 37, and adjacent the extreme end of the part 37 of the slot, the drip pipe 32 is provided with an eye stud or apertured lug 38 which co-operates with the eye 50 stud 34 in locking the parts together. Obviously, the pipe 33 may be raised to cover 55 the discharge spout 8 by lifting up on the eye stud 34 and moving it along the part 37 of the slot until it is brought close to the eye stud 38, and the parts may be locked in such position by an ordinary padlock 39.

60 To insure a secure closure for the discharge spout, an overhanging flange member 40 is provided on the nozzle 7 into which the pipe 33 is introduced. Said flange member 40 may also be employed as a means of connecting the discharge spout 8 with the re-

mainder of the nozzle. As shown, the nozzle is formed with a screw threaded nipple 41 at its discharge end, and the discharge spout is formed with an outwardly projecting flange or bead 42 which bears against 70 the edge of the nipple 41, and the flange member 40 is formed with an internal annular flange 43 that bears against the flange or bead 42 of the spout. By screwing up the flanged member 40 on the nipple, the spout 75 is securely fastened in place.

When the parts are locked together, the pipe 33 extends above the drip pipe 32, and surrounds and encloses the discharge spout 8, with its extreme upper end confined in the 80 flanged member 40. In this position, the cover cannot be removed and access to the tank is impossible without breaking any of the parts or unlocking the lock. In this position of the parts, any oil pumped out of 85 the tank through the discharge spout will pass directly back to the tank. To uncover the spout, the padlock 39 is unlocked and removed from the apertured lug 34 and eye stud 38, the pipe 33 is telescoped into the 90 drip pipe 32 and the cover 24 swung away from the drip pan 13. A receptacle may then be placed under the spout and oil may be dispensed into it from the tank, as usual. Any drippings issuing from the spout, after 95 the receptacle is removed, will fall through the central openings in the grid and enter the tank. The drip pan may be readily removed when the cover plate is swung back and access to the tank through the opening 100 is thereby afforded for filling purposes. To lock the parts, the cover plate 24 is moved back upon the ring 10, the pipe 33 raised into the flanged member 40 and the padlock 39 applied to the two eye studs 34, 38. 105

In the modified form of the invention, illustrated in Figs. 6 to 8, inclusive, the grid or grate 19^a is made separate from the drip pan or bottom plate 14^a and both the grid or grate 19^a and the cover 24^a are hinged to the 110 flanged ring 5^a to swing in a vertical plane. The hinge connection, as shown, comprises ears 5^b formed on the ring 5^a and ears 19^b, 24^b, formed respectively on the grid 19^a and cover 24^a, and a pivot pin 25^a which extends 115 through said ears and is headed on the outside thereof.

The lock for the cover and grid may comprise the drip pipe 32^a and locking connections as in the preferred form, or the grid 120 and cover may be locked to the ring 5^a by an upstanding lug 34^a formed on an ear 28^a of the ring, said lug being arranged to project up through slotted ears 19^c, 26^c, formed respectively on the grid 19^a and cover 24^a. 125 Holes 34^b, 34^c, are formed in said lug 34^a, one hole above the ear 19^c and one above the ear 24^c for the reception of the bow of a padlock 39^a. By inserting the bow through the hole 34^b, both cover and grid may be locked 120

and by inserting the bow through the hole 34^c, the grid alone may be locked, although permitting the cover to be opened.

The handle 22^a of the measuring stick or 5 gauge 21 is notched as seen in Fig. 8 and one of the ribs 19^x of the grid 19^a is so positioned that when the grid is swung down into place, said rib 19^x enters the notch of the handle 22^a and prevents removal of the measuring 10 stick, except when the grid is unlocked and raised.

It is to be noticed that the cover in each form of the invention illustrated, covers the bolts, screws or rivets that fasten the ring 15 to the tank. This arrangement prevents the device from being removed from the tank when the parts are locked. Obviously, the drip pipe may be dispensed with and the cover may be made solid in place of forming 20 it with the hole for said drip pipe. Moreover, the grid or grate plate may be removed to leave a large opening for filling purposes. The parts are simple, easily assembled and 25 not likely to get out of repair. When the cover is locked, access to the interior of the tank is impossible and its contents cannot be disturbed. The cover, shown in the modified form, may be unlocked during working 30 hours, and the grid alone locked, thereby permitting the cover to be swung back to permit receptacles to be placed on the grid when filling them. The measuring stick 35 being locked in place, no opening is presented through which any of the contents may be removed except through the screen and then only by destroying the screen or inverting the entire tank.

More or less variation of the exact details 40 of construction is possible without departing from the spirit of this invention; we desire, therefore, not to limit ourselves to the exact form of the construction shown and described, but intend, in the following 45 claims, to point out all of the invention disclosed herein.

We claim as new and desire to secure by Letters Patent:

1. In combination with a tank having an

opening therein, of a drip pan ring in said opening, securing means for fastening said 50 ring to the tank, a grid in said ring, a cover hinged to said ring and covering said ring fastening means, and locking means for locking said cover on said ring.

2. In combination with a tank having an 55 opening therein, of a drip pan ring in said opening, securing means for fastening said ring to the tank, a grid in said ring, having a hole for the reception of a measuring stick, a measuring stick extending through said 60 opening and having a head covering said opening, a cover hinged to said ring and covering said ring fastening means, and locking means for locking said cover on said ring.

3. In combination with a tank having an 65 opening therein, of a drip pan ring in said opening, a grid, and a cover hingedly secured to said ring on a horizontal axis, whereby said grid and cover may be swung 70 in a vertical plane, and a single lock for locking both the grid and cover on said ring.

4. In combination with a tank having an 75 opening therein, of a flanged drip pan ring in said opening, a drip pan supported in said flanged ring, a measuring stick extending through a hole in said drip pan and having a head resting thereon, a grid and a cover hingedly connected to said ring, said grid having a web overlying said head of 80 the measuring stick, and means for locking said grid to said ring independently of the cover.

5. In combination with a tank having an 85 opening therein, of a flanged drip pan ring secured in said opening, a centrally apertured drip pan supported by said ring and having a screen covering said opening, a grid and a cover hingedly secured to said ring and adapted to be swung over said drip pan, 90 and means for locking the drip pan alone and for locking the drip pan and cover to the ring.

ANDREW D. WYCKOFF.
HOWARD P. DE CORREVONT.
